C. E. WILLIAMS

CARBURETOR

Filed Sept. 29, 1924

UNITED STATES PATENT OFFICE.

CHARLES E. WILLIAMS, OF DETROIT, MICHIGAN, ASSIGNOR TO GENERAL MOTORS CORPORATION, OF DETROIT, MICHIGAN, A CORPORATION OF DELAWARE.

CARBURETOR.

Application filed September 29, 1924. Serial No. 740,480.

This invention relates to carburetors, and is illustrated as embodied in a carburetor of the type used on the Cadillac automobile.

An object of the invention is to guard 5 against "fluttering" of the auxiliary air valve, due to coincidence of the period of vibration of the auxiliary air valve with the period of the suction impulses from the engine at a certain speed when the throttle 10 approaches open position. In one desirable arrangement, fluttering is prevented by making the auxiliary air valve in two parts having different periods of vibration, so that any vibrations of one part are damped 15 out by the other part.

From a somewhat different point of view, another object of the invention is to provide means for relieving pressure in the carburetor in case of back-firing from the 20 engine, by providing an outwardly opening valve member. Preferably this member forms one of the above-described parts of the auxiliary air valve.

In the particular embodiment illustrated 25 in the drawings, the auxiliary air valve includes an inwardly-opening pivoted disk, having an opening or port therethrough which is normally closed by a pivotally-mounted auxiliary disk or valve member, 30 weighted to have a different period of vibration from the inwardly-opening disk, and which can yield in case of back-firing.

The above and other objects and features 35 of the invention, including various novel and desirable details of construction, will be apparent from the following description of one illustrative embodiment shown in the accompanying drawings, in which:

Figure 1 is a side elevation of a carburetor, broken away to show the auxiliary air valve in vertical section;

Figure 2 is an end elevation of the carburetor, broken away to show the auxiliary air valve spring;

Figure 3 is a bottom plan view of the auxiliary air valve and the adjacent part of the carburetor casing; and

Figure 4 is a section corresponding to part of Figure 1, but showing the auxiliary air valve open, with the outwardly-opening part damping out the "fluttering" action.

In the arrangement selected for illustration, the carburetor comprises a float chamber 10 below the usual fuel nozzle and primary air intake (not shown in detail), at

one side of which is the auxiliary air chamber 12, and at the other side of which is a throttle pump 14 operated by the throttle shaft 16 when the throttle is opened suddenly to force extra fuel through the fuel nozzle, temporarily to enrich the mixture. A flange 18 is provided for attaching the carburetor to the intake manifold or connections. Except as further described below, these parts or their equivalents may be 65 of any desired construction.

In the air chamber 12 is a flanged opening 20 forming an air intake passage, controlled by an auxiliary air valve including a disk 22, having an opening or port 24, and carried by an arm 26 pivoted on a spindle 28. Disk 22 opens, to admit air, against the resistance of a compression spring 30 secured to a split clamp 32 secured to a spindle 34. Spindle 34 may be rocked to increase the 70 resistance of the spring, when starting the engine, by an arm 36. The ordinary running position of spindle 34 is adjustably determined by a setscrew 38 engaging the clamp member 32.

Opening or port 24 is normally closed by an auxiliary disk 40, engaging the bottom of disk 22, and carried by a forked arm 42 pivoted on spindle 28. The forks of arm 42 are extended to support a weight 44 yielding holding disk 40 in position against disk 22 closing the opening 24. The parts described above are so weighted that disks 22 and 40 have different periods of vibration. Thus when, as shown in Figure 4, "fluttering" starts, disk 22 swings away from disk 40, so that the non-synchronous movement of the two disks quickly damps out the "fluttering" vibrations. Since disk 40 opens outwardly, it can yield in case of 85 back-firing.

While one illustrative embodiment of the invention has been described in detail, it is not the intention to limit its scope to that particular embodiment, or otherwise than 100 by the terms of the appended claims.

I claim:

1. A carburetor having, in combination, a chamber having an auxiliary air passage, and an auxiliary air valve in two parts controlling said passage, the parts being separately movable in the line of air flow and normally in contact with each other, and being so weighted that they cannot both oscillate at the same rate.

2. An auxiliary air valve comprising a pivoted disk opening upward in response to engine suction and formed with an opening, and a second disk pivoted for movement concurrently with the first disk and counter-weighted to be held normally against the first disk to close said opening.
3. An auxiliary air valve comprising a fulcrum pin, an arm pivoted thereon, a valve disk carried by the arm and formed with an opening, a second arm pivoted on the fulcrum pin, a disk carried by the second arm, and means acting on the second arm yieldingly holding its disk against the valve disk over said opening.
4. A carburetor comprising, in combination, a chamber having an auxiliary air inlet passage, and a non-fluttering auxiliary air valve controlling said passage and consisting of a valve member movable to open or close or restrict the opening and which is formed with a port therethrough, and a counter-weighted swinging cooperating member normally moving with the valve member and closing the port but which can open outwardly in case of back-firing or in case of fluttering.

In testimony whereof I affix my signature.

CHARLES E. WILLIAMS.
